UNITED STATES PATENT OFFICE.

ANDREW S. NELSON, ALBERT STEWART, AND THOMAS JOHNSON FOSTER,
OF MOTHERWELL, SCOTLAND.

FOUR-WHEELED TRUCK FOR TRAMWAY-CARS, RAILWAY-CARRIAGES, &c.

SPECIFICATION forming part of Letters Patent No. 737,132, dated August 25, 1903.

Application filed December 27, 1902. Serial No. 136,835. (No model.)

To all whom it may concern:

Be it known that we, ANDREW SCLANDERS NELSON, ALBERT STEWART, and THOMAS JOHNSON FOSTER, subjects of the King of the 5 United Kingdom of Great Britain and Ireland, all residing at the Glasgow Rolling Stock and Plant Works, Motherwell, in the county of Lanark, Scotland, have invented 10 certain new and useful Improvements in Four - Wheeled Trucks for Tramway - Cars, Railway - Carriages, and Like Vehicles, (for which application for patent has been made in Great Britain, No. 13,909, dated June 19, 1902,) of which the following is a specification.

This invention relates to trucks for tramway-cars, railway-carriages, and like vehicles, where a portion of the weight of the body is carried upon springs supported on the extended ends of the side bars; and the invention consists in the arrangement and combination of parts constituting the truck, and more especially in the provision of laminated springs of variable tension at the end of solid bars and of body horn - bars in conjunction with the usual truck-horn bars.

In the drawings, Figure 1 is an elevation, and Fig. 2 a plan, of an improved four-wheeled truck-frame constructed according 30 to our invention. Fig. 3 is a side elevation of a part of the structure on a larger scale. Fig. 4 is a sectional plan on line X X of Fig. 3. Fig. 5 is an edge view of the body horn-bar.

As shown in the drawings, the truck comprises solid side bars A, preferably of rolled angle steel or iron, to which separate horn-bars or pedestals B, of cast or pressed steel or iron, are connected, while to the truck top bars C are secured body horn-bars D of mild steel or iron plates suitably shaped for the purpose of preventing pitching of the vehicle. Each of the body-bars D may work in the same slide or groove as the truck horn-bars B or in an independent groove in the axle-box E. To the bottom of the body horn-bars D, on each side of the vehicle, is attached a stretcher-bar F, preferably of iron or steel tube with solid ends. The stretcher-bars F may be in one or more pieces and may be 45 used in conjunction with a strut extending between the leg of the horn-bar D and the

body of the vehicle, or it may also be used in combination with an adjusting - screw or screws for the purpose of acting as a body-truss.

The end springs G are preferably of the laminated type, with solid or curled eyes H, and provided with tensional adjusting-screws J for the purpose of regulating the height and stiffness. The tensional screws J are 55 fitted with nuts for the purpose of adjustment and pass through and are carried in suitable scroll-irons secured to the truck top bar C.

Intermediate springs M, preferably of the conical spiral type, sitting in spring-shoes N of pressed steel, are provided with adjusting-bolts O, acting upon the truck top bar C and upon check-springs P, placed underneath for the purpose of preventing galloping of the vehicle. Diagonals Q, of suitable angle or other 60 sectional steel or iron, are attached to the truck side bars A and to each other and are arranged to carry the motor suspension-bars R. Suitable cross-bars S are provided in the truck to answer the purpose of carrying the 65 brake and also to tie the sides together. Pilot-irons U are provided at or near the ends of the side bars A for the purpose of carrying the pilot-board U' and which may be of the usual type. The brake-blocks V are preferably of 70 the detachable type and are attached to the cross-bars S, fitted with application-levers X, worked by means of rods and chains secured to the brake-shaft.

It will be understood that in practice modifications of the specific constructions shown may be made and any suitable materials and proportions may be used for the various parts without departing from the spirit of the invention.

Having now described the invention, what we claim, and desire to secure by Letters Patent, is—

1. The herein-described four-wheeled truck comprising in combination solid side bars, 85 pedestals or truck horn-bars secured to said side bars truck top bars, body horn-bars secured to said top bars sliding in the same grooves as the pedestals, stretcher-bars connecting the body horn-bars, end laminated 90 springs connecting the side bars to said top bars, means for adjusting the tension of said 100

- 5 springs, intermediate helical springs, spring-shoes underneath the top bars upon which said intermediate springs bear, check-springs underneath the side bars, bolts connecting said intermediate springs with said check-springs, diagonals attached to the side bars and to each other, motor suspension-bars connected to said diagonals, cross-bars connecting said side bars and carrying the brakes, 10 and pilot-bars at the ends of said bars substantially as and for the purpose set forth.
2. In a four-wheeled truck constructed as described the combination with solid side bars and truck top bars of pedestals or truck horn-bars secured to the side bars, body horn-bars secured to the top bars, and sliding in the same groove as the pedestals, and compression-springs interposed between the side bars and top bars as and for the purpose set forth.
- 15

3. In a four-wheeled truck constructed as 20 described, the combination with solid side bars and truck top bars of truck horn-bars secured to the side bars, body horn-bars secured to the top bars and sliding in the same groove as said truck horn-bars, laminated end springs 25 connecting said side bars and said truck top bars, means for adjusting said end springs, and intermediate compression-springs interposed between said side bars and said top bars for the purpose set forth.

30 In witness whereof we have hereunto set our hands in presence of two witnesses.

ANDREW S. NELSON.

ALBERT STEWART.

THOMAS JOHNSON FOSTER.
